(57) **CLAIM**

The ornamental design for an ear cleaning device, as shown and described.

DESCRIPTION

FIG. 1 is a perspective view of an ear cleaning device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the ear cleaning device with additional broken line environment.

The broken lines in the drawings depict portions of the ear cleaning device that form no part of the claimed design.

1 Claim, 9 Drawing Sheets
